UNITED STATES PATENT OFFICE

GEORGE T. JACOCKS, OF BROOKLYN, NEW YORK, ASSIGNOR, BY MESNE ASSIGNMENTS, TO ALCO PRODUCTS INCORPORATED, OF NEW YORK, N. Y., A CORPORATION OF DELAWARE

CONDENSER

Application filed April 4, 1929. Serial No. 352,344.

This invention relates to small condensers used in connection with refrigerating machines and the like, wherein it is necessary to cool or condense gases or vapors by the abstraction and dissipation of the heat contained therein.

An object of the invention is to provide an efficient condenser of simpler, cheaper and more rugged form than has heretofore been available.

Condensers of this class have heretofore been fashioned of expensive materials and in an intricate manner; usually comprising an assemblage of pipes or tubes in coiled or nested arrangement.

The improvement claimed is hereinafter fully set forth.

In the accompanying drawing: Fig. 1 is a view in elevation partly in section of a condenser; Fig. 2, a section in elevation on the line 2—2 of Fig. 3; Fig. 3, a plan view of Fig. 2; and Fig. 4, a view in elevation with a portion of the outer wall broken away, showing a modified form of construction wherein the successive helices of the helical member are spaced decreasing distances apart.

In the practice of the invention, referring descriptively to the specific embodiment thereof which is herein exemplified, a leading and characteristic feature of novelty thereof is a spaced, helical, passage forming member 1, positioned between the inner shell 2, and the outer shell 3, and in intimate contact with both, forming the passage A. Annular heads 4, 4a, are fitted between the shells 2, 3, adjacent their extremities, and preferably secured by welding thereto as shown. An inlet 5, is formed at one end of the passage A, and an outlet 6, adjacent the other end of said passage. A hollow member 7, is positioned encompassing the upper end of the shells, and is fitted with a narrow space 7a separating it from the shell 3, and a similar space 7b separating it from the shell 2. Water from a suitable supply is admitted to said hollow member 7, by a suitable conduit, as at 7c, so that said water may flow over the external walls of the said shells through the formed narrow spaces 7a and 7b.

The invention is preferably constructed in

the following manner:—An inner shell 2, formed of commercial pipe, has helically coiled upon it a bar of iron of substantially circular cross section. This coiling is accomplished whilst the bar is hot, and the coils are wound in a predetermined spaced relation. In cooling, the helix thus formed shrinks upon the shell 2 to grip it tightly. The shell 2, with the thus formed helix upon it, is then placed in a turning lathe or equivalent engine, and the outer periphery of the helix 1, is formed to a uniform contour of such dimension that the outer shell 3, may, after heating, be slipped over said helix 1, and when cooled shrink to grip said helix 1 tightly.

The above described method results in forming a helical passage of greater width adjacent the shells than intermediate thereof, the oppositely disposed convex walls of the bar forming the helix 1, causing the passage between to be of throat-shaped, or centrally contracted cross section.

Gas or vapor admitted to the condenser by the means 5, and caused to flow through the helical passage therein formed as above described is rapidly and efficiently cooled by reason of the increased relation of cooling surface comprised by the walls of the shells 2, 3, contacting with the flowing gas, to the cross sectional area of the passage, incident to its throat like formation.

After cooling, the gas has a greatly reduced specific volume, or may, in the case of a vapor, be condensed to a liquid, and is discharged from the condenser through the means 6, shown in the drawing as penetrating and affixed to the annular head 4a, but which may be attached to the condenser in any other manner provided said means serves for the eduction from the condenser of the cooled fluid after said fluid has passed through said helical passage.

To effect the rapid dissipation of heat from the walls of the shells 2, 3, there is positioned on their upper extremities the hollow member 7, comprising annular walls encompassing said shells, and so disposed with respect thereto as to form narrow openings 7a, 7b through which thin sheets of water may be

caused to flow over the exterior walls of said shells 2, 3. A suitable source of water supply is connected to the hollow member 7 at the inlet 7c.

6 The efficiency of the condenser is greatly dependent upon the manner of positioning the helix 1, within the shells 2, 3, and it is desired to have the successive turns of said helix so spaced that the resulting passageway between them shall expose the greatest surface of the condensing walls of the shells 2, 3, in proportion to the net cross sectional area of said passage, that is consistent with the desired rate of flow of the said fluid therethrough. Hence it follows that whereas the helix may commonly be formed with a uniform pitch, that for maximum efficiency it may be wound with a decreasing pitch; so that as the gas cools and decreases in specific 20 volume, it may flow through the helical passage at constant velocity or resistance; the decreasing cross sectional area of the passage corresponding to the decreasing specific volume of the fluid as cooling progresses.

25 In Fig. 4 of the drawing a modified form of construction is shown wherein the successive helices of the helix 1 are spaced decreasing distances apart.

A condenser formed as above described, is 30 of simple, rugged, and cheap construction, combined with high efficiency; and is especially suited to small, isolated plants, such as refrigerating machines of moderate capacity, where inspection is awkward or 35 infrequent.

The invention claimed and desired to be secured by Letters Patent is:

1. In a condenser, the combination of a passageway for the traversing of the vapor to be condensed, comprising spaced inner and outer walls, at least one of which walls having its exterior surface freely exposed to the atmosphere, baffling means between the walls compelling the vapor to take a winding route therebetween, and inlet and outlet openings for the admission of vapor and the exit of condensation; and means for applying to the exposed exterior surface of one of the walls a thin sheet of condensing water.
2. In a condenser, the combination of a passageway for the traversing of the vapor to be condensed, comprising spaced inner and outer walls continuous in cross section, at least one of said walls having its exterior surface freely exposed to the atmosphere, baffling means between the walls compelling the vapor to take a helical route around the passageway in travelling therethrough, and inlet and outlet openings for the admission of vapor and the exit of condensation; and means for applying to the exposed exterior surface of one of the walls a thin sheet of condensing water.
3. In a condenser, the combination of a 45 passageway for the traversing of the vapor to

be condensed, comprising spaced walls continuous in cross section, baffling means therebetween compelling the vapor to take a helical route around the passageway in travelling therethrough, and inlet and outlet 70 openings for the admission of the vapor and the exit of the condensation; and means whereby a thin sheet of condensing water is passed over the exterior surface of the outer wall of said passageway. 75

4. In a condenser, the combination of a passageway for the traversing of the vapor to be condensed, comprising spaced walls having baffling means therebetween compelling the vapor to take a winding route 80 therethrough, and inlet and outlet openings for the admission of the vapor and the exit of the condensation; and a header having a wall cooperating with a wall of the passageway to form a narrow slit therebetween for 85 the passage of a film of water over the wall of the passageway.

5. In a condenser, the combination of a passageway for the traversing of the vapor to be condensed, comprising spaced walls 90 continuous in cross section, a helical partition encircling the passageway and extending longitudinally thereof compelling the vapor to take a winding route around the passageway following the direction of the partition, and 95 inlet and outlet openings for the admission of the vapor and the exit of the condensation; and means whereby a thin sheet of condensing water is passed over the exterior surface of a wall of said passageway. 100

6. In a condenser, the combination of a passageway for the traversing of the vapor to be condensed, comprising spaced walls and baffling means therebetween compelling the vapor to take a winding route therethrough, 105 and inlet and outlet openings for the admission of the vapor and the exit of the condensation; and a header having a wall for each of the walls of the passageway, spaced therefrom to provide narrow slits therebetween 110 for the passage of films of water over the walls of the passageway.

7. In a condenser, the combination of a passageway for the traversing of the vapor to be condensed, comprising spaced walls and 115 baffling means therebetween compelling the vapor to take a winding route therethrough; and a header having a wall cooperating with a wall of the passageway to form a narrow slit therebetween for the passage of a film of 120 water over the wall of the passageway, said passageway having a portion of its walls extending into said header and provided with an outlet in the extended portion and an inlet at the opposite end of the passageway. 125

8. In a condenser, the combination of a passageway for the traversing of the vapor to be condensed, comprising spaced walls and baffling means therebetween compelling the vapor to take a winding route therethrough; 130

- and a header having a wall cooperating with a wall of the passageway to form a narrow slit therebetween for the passage of a film of water over the wall of the passageway, said passageway having an outlet passing through said header and an inlet at the opposite end of said passageway. 70
9. In a condenser, an inner shell; a spaced, helical, passage-forming member pressure fitted upon said inner shell; an outer shell, pressure fitted upon said helical member; annular heads closing the space between said outer and inner shells, and secured thereto adjacent the ends thereof; means for admitting fluid to one end of said condenser and for educting said fluid from the other end of said condenser and a header having a wall co-operating with one of said shells to form a narrow slit therebetween for the passage of a film of water therethrough. 85
10. In a condenser, an outer shell; an inner shell; a helical passage forming member having oppositely disposed convex walls interposed between the shells; means for ingress and egress of fluid to and from the formed helical passage; annular heads enclosing the space between the shells at the ends thereof and hermetically secured thereto; a hollow member encompassing one end of said condenser and spaced therefrom to permit a thin sheet of water to flow from said hollow member over the exterior walls of said shells; and means for supplying water to said hollow member. 90
11. In a condenser, an inner shell; a helical member mounted on said inner shell, the helices of said member being variably spaced; an outer shell mounted on said helical member; heads hermetically sealing the space between said shells adjacent the ends thereof; and water distributing means for wetting the exterior walls of said shells. 100
12. In a condenser, spaced inner and outer shells having an inlet at one end and an outlet at the other end to and from said space; a helical partition of uniform internal diameter within said space extending between the inlet and outlet, the spaces between the windings of the partition decreasing toward the outlet in a predetermined manner; and means for applying a stream of water to the exterior of one of the shells. 105
13. In a condenser, the combination of a passageway for the traversing of vapor and condensate thereof, comprising spaced inner and outer walls, at least one of which walls having its exterior surface freely exposed to the atmosphere, helical baffling means between the walls compelling the contents thereof to take a winding route therebetween, and inlet and outlet openings for admission of vapor and the exit of condensation; a hollow member encompassing one end of said condenser and spaced from said inner and outer walls to provide narrow slits therebetween. 115
14. In a condenser, spaced inner and outer shells having an inlet at one end and an outlet at the other end to and from said space; a helical partition of uniform internal diameter within said space extending between the inlet and outlet, the spaces between the windings of the partition decreasing toward the outlet in a predetermined manner; and means for applying a stream of water to the exterior of one of the shells. 120
15. In a condenser, spaced inner and outer shells having an inlet at one end and an outlet at the other end to and from said space; a helical partition of uniform internal diameter within said space extending between the inlet and outlet, the spaces between the windings of the partition decreasing toward the outlet in a predetermined manner; and means for applying a stream of water to the exterior of one of the shells. 125
16. In a condenser, spaced inner and outer shells having an inlet at one end and an outlet at the other end to and from said space; a helical partition of uniform internal diameter within said space extending between the inlet and outlet, the spaces between the windings of the partition decreasing toward the outlet in a predetermined manner; and means for applying a stream of water to the exterior of one of the shells. 130
